CELLULOSE DIGESTER

Friedrich Wilhelm Ludwig Schilder,
Graz, AustriaApplication November 4, 1935, Serial No. 48,241
In Austria November 10, 1934

4 Claims. (Cl. 92—7)

This invention relates to cellulose digesters. As is well known in the art, these digesters are provided with special means or devices for evacuating the digester before commencement of the boiling (provided such evacuating be contemplated), as also for introducing the lye, for turning over the liquor in the digester (when necessitated by close packing of the charge of wood chips or the like), and for the feeding in of steam. 5
10 In the hitherto known types of apparatus of this description, the digester is evacuated either by means of vapors or by means of an air pump or mechanical blower, and that before admission of the boiling lye and after the digester has been firmly closed down, or by letting out a portion of the lye after the filling and closing down of the container. When direct heating of the contents of the digester is adopted, the steam is fed in through one or more perforated pipe coils. When 15
20 indirectly heating of the contents of the digester is adopted, either tubes of acid-proof material are built into the interior of the digester, in which tubes the steam is condensed and rendered available for other purposes, without diluting the digesting lye, or preheaters, likewise of acid-proof material, are provided outside the digester. If it should be necessary, in consequence of tight packing of the charge of chips, to circulate the lye for the purpose of heating the same to a uniform 25
30 temperature and of preventing the formation of cold pockets, there is usually employed a mechanical pump which must of course be made of acid-proof material, and which can be disposed either inside or outside the digester. In the former case the pipes required to carry the lye can also be provided in the interior of the digester. The lye can either be withdrawn from the digester at the top and returned under pressure at the bottom, or vice versa. The direction of flow can 35
40 also be made to alternate.

The present invention is concerned with a cellulose digester equipped with means for evacuating the container before commencement of the boiling, for feeding in the lye, for circulating the liquor, and for discharging the contents and/or introducing the washing water, as also for feeding in the steam; the essential feature of the invention being that for effecting all the feeding, evacuating, and circulating required there are employed exclusively steam- or gas-jet devices disposed outside the digester proper, suitably grouped, and connected to the digester by means of appropriate controllable valve members disposed outside the digester. The jet device employed for evacuation is independent of those

serving for circulating and heating. By this arrangement of the jet devices for circulating and heating in a convenient position at the operative's stand, the work of tending and controlling the entire boiling process is very greatly facilitated. 5
10 At the same time the replacement of the power-consuming circulating pump by this more suitable and simpler fluid-jet impelling device enables the energy contained in the steam supply to be made use of for effecting circulation of the lye.

The evacuation of the digester and of the chips or other matter constituting the charge results in uniform and immediate penetration of the lye into the material of the charge, and consequently in uniform and undelayed dissolving of the encrusting matter and/or uniform decomposition of the wood, and therefore also in improved strength and whiteness of the cellulose obtained, and in the obtaining of higher yields which means greater economy in the consumption of the starting material used. 15
20

The lay-out of the plant is extremely compact, since one and the same set of apparatus can be used for a plurality of operations in the course of the digesting process. Furthermore, no rotating parts are used, and the wear involved therein is consequently avoided. 25

A form of construction embodying the invention is shown, by way of example, in the accompanying drawing in which Fig. 1 shows a digester in accordance with the invention in longitudinal section, while Fig. 2 shows a detail of the same. 30

In the drawing, 1 denotes the digester which is provided at the top with a feed pipe connection 2 for the introduction of the charge and at the bottom with a discharge pipe connection 3. The usual gas escape pipe 4, which branches off the feed pipe connection 2, is also connected, with the interposition of a stop-cock 5, to a steam-jet exhauster 5^a to which steam is fed through the pipe 5^b, for the purpose of evacuating the container after the introduction of the charge. On the outside of the digester there are provided further steam jet devices in the form of injectors 6, 7, and 8 which are connected on the one hand, 35
40 through valves 6^a, 7^a, 8^a, by branches, to a common steam supply pipe 9, and on the other hand through valves V₁, V₂, V₃ and branches to a pipe cross 10. From this cross 10 pipes 11a and 11b branch off, through valves 12a and 12b, to the lye 45
50 container and to the water tank, respectively, while a pipe line 13 leads to a perforated tubular ring 14 disposed in the upper part of the digester. The down-pipes from the steam jet devices 6, 7, and 8 merge at 15 into a common pipe 16 which 55

either discharges with its full bore into the lower part of the digester or is branched to two connections 17 and 18 communicating with perforated tubular rings 19 and 20 disposed in the lower 5 part of the digester 1, a pipe 22 being also branched off and discharging into the bottom of the discharge connection 3. The usual lye outlet is provided at 21 in the pipe 16.

The mode of operation of the apparatus according to the invention is as follows:—

The digester is first charged up to the rim with the material to be digested. After the closing of the upper man-hole 2 and of all other apertures and valves associated with the entire 15 digester, the container is evacuated by means of the steam jet exhauster 5^a, with the result that the air contained in the pores of the charge escapes, and the lye introduced in the succeeding phase of the procedure can penetrate right 20 into the interior of the shreds or other material constituting the charge. On opening the valve 12^a, valves V₁, V₂, V₃, and steam valves 6^a, 7^a, 8^a, the lye is introduced and at the same time heated by means of the steam jet injectors 6, 7, 25 and 8. When the digester has been filled with lye, which can be effected to a lower level than is otherwise usual on account of the preceding evacuation, the process of boiling is commenced. During the boiling the lye is turned over or circulated 30 in the digester. To this end, the lye is withdrawn from the top of the container through the perforated tubular ring 14 by means of the same steam jet devices 6, 7, and 8 as are employed for feeding in the lye, and returned to the digester at the bottom through the perforated tubes 35 19 and 20 and pipe 22. At the same time the work performed in circulating the liquor can be regulated by turning on or off one or more of the steam jet devices constituting the set. During 40 the circulating operation the valves 12^a and 12^b in the pipe lines 11^a and 11^b are closed. To prevent excess pressure, the mixture of the gas generated in boiling, with liquid and vapour is drawn off, in the usual manner, from the top of 45 the digester through the pipe 4 and returned to the lye containers, although this venting can be postponed to a later time than is otherwise usual since in consequence of its evacuation the digester is filled to a lower level with lye and consequently 50 more space is provided for the condensate of the boiling steam supplied. Should too much lye happen to become unintentionally introduced into the digester the excess can be returned into the lye containers through a small valve which may 55 be provided for instance on the cross 10 and adjoining pipe, thus preventing premature escape of the more valuable gas. When the boiling process is concluded the pressure is relieved, in the usual manner, by letting out the gas, after 60 which the lye is removed by opening of the valve 21. Washing water is then forced into the bottom of the digester by opening the valve 12^b, the three valves 6^a, 7^a, 8^a, and the steam jet devices 6, 7, and 8, whereupon the outlet 3 at the bottom 65 of the container is opened and the digester emptied, accelerated and thorough emptying as also scouring being thereby ensured.

I claim:

1. Apparatus for the preparation of cellulose comprising a boiler, a closure extension at the top of the boiler, a steam jet impelling device connected by a pipe line to the upper part of the

boiler and by a further pipe line to the lower part of the boiler and by a third pipe line to a steam generator, control valves in the said pipe lines adapted to permit, selectively, of the feeding of steam to the boiler, feeding of lye into the boiler, and circulation of the contents of the boiler by removal from the upper part and returning under pressure into the lower part of the boiler, and a steam jet exhauster connected to the said closure extension for the purpose of evacuating the boiler before commencement of boiling.

2. Apparatus for the preparation of cellulose comprising a boiler, a closure extension at the top of the boiler, a plurality of steam jet impelling devices connected to a common pipe line 15 communicating with the upper part of the boiler and to a further common pipe line communicating with the lower part of the boiler, and connected by a third pipe line to a steam generator, control valves in the said pipe lines adapted to 20 permit, selectively, of the feeding of steam to the boiler, introduction of lye into the boiler, and circulation of the contents of the boiler by removal from the upper part and returning under pressure into the lower part of the boiler, and a 25 steam jet exhauster connected to the said closure extension for the purpose of evacuating the boiler before commencement of boiling.

3. Apparatus for the preparation of cellulose comprising a boiler, a closure extension at the 30 top of the boiler, a plurality of steam jet impelling devices adapted to be shut off and turned on independently and selectively and combined to form a unit, the said unit being connected to a common pipe line communicating with the 35 upper part of the boiler and to a further common pipe line communicating with the lower part of the boiler, and being connected by a third pipe line to a steam generator, control valves in the said pipe lines adapted to permit, selectively, of the feeding of steam into the boiler, introduction of lye into the boiler, and circulation of the contents of the boiler by removal from the upper part and returning under pressure into the lower part of the boiler, and a steam 45 jet exhauster connected to the said closure extension for the purpose of evacuating the boiler before commencement of boiling.

4. Apparatus for the preparation of cellulose comprising a boiler, a closure extension at the 50 top of the boiler, a perforated tubular ring disposed in the interior of the boiler, a second tubular ring with outlet apertures disposed in the lower part of the boiler, a plurality of independently and selectively controllable steam jet impelling devices combined to form a unit, the said unit being connected to a common pipe line communicating with the said first tubular ring and to a further common pipe line communicating with the said second tubular ring, and by a third 55 pipe line to a steam generator, control valves in the said pipe lines adapted to permit, selectively, of the feeding of steam to the boiler, introduction of lye into the boiler, and circulation of the contents of the boiler by removal from the upper part and returning under pressure into the lower part of the boiler, and a steam jet exhauster connected to the said closure extension for the purpose of evacuating the boiler before 60 commencement of boiling.
